CLAIM

The ornamental design for a toy seahorse, as shown and described.

DESCRIPTION

FIG. 1 is a front perspective view of an ornamental design for a toy seahorse;

FIG. 2 is a rear perspective view thereof;

FIG. 3 is an underside perspective view thereof;

FIG. 4 is a front elevation view thereof;

FIG. 5 is a rear elevation view thereof;

FIG. 6 is a left side view thereof;

FIG. 7 is a right side view thereof;

FIG. 8 is a top plan view thereof;

FIG. 9 is a bottom plan view thereof;

FIG. 10 is a front perspective view thereof;

FIG. 11 is a front elevation view thereof;

FIG. 12 is a top plan view thereof; and,

FIG. 13 is a bottom plan view thereof.

The broken lines in the figures are included to show unclaimed subject matter only and form no part of the claimed design.
